UNITED STATES PATENT OFFICE.

JOSEPH D. MARTINEZ, OF WHITECASTLE, LOUISIANA.

CANE-LOADING MACHINE.

SPECIFICATION forming part of Letters Patent No. 672,789, dated April 23, 1901.

Application filed October 15, 1900. Serial No. 33,126. (No model.)

To all whom it may concern:

Be it known that I, JOSEPH D. MARTINEZ, a citizen of the United States, residing at Whitecastle, in the parish of Iberville and State of Louisiana, have invented certain new and useful Improvements in Cane-Loading Machines; and I do hereby declare the following to be a full, clear, and exact description of the invention, such as will enable others skilled in the art to which it appertains to make and use the same.

My invention relates to improvements in cane-loaders; and it consists of the machine having devices for picking up, elevating, and turning the cane in position for loading upon a vehicle, and, finally, for dropping it upon such vehicle, all as will be hereinafter fully described and claimed.

Reference is had to the accompanying drawings, in which the same parts are designated by the same letters of reference throughout the several views, and in which—

Figure 1 represents a side elevation of the entire machine. Fig. 2 represents a plan view 25 of the same with the top platform and revolving arms removed and shown in dotted lines. Fig. 3 represents a side elevation of the mechanism for raising and lowering the front part of the machine. Fig. 4 represents 30 a plan view of the top platform removed from the machine. Fig. 5 is a detail view showing a side elevation and plan view of a part of one of the carrier-chains.

The several devices comprising my machine 35 are mounted upon a rectangular frame composed of the side beams A A, the cross-beams A' A', the uprights A² and A³, and the upper platform-beams A⁴. The frame is braced at the corners and junctions of the beams by 40 braces A⁵ and also has brace-beams A⁶ extending from the upper platform to near the forward end of the side beams A. The rear part of the frame is supported on wheels B, and the forward portion of the frame is supported upon a frame C, carried upon the 45 wheels C'. The frame C is connected with the main frame by links C² and C³, which are pivoted at their front ends to the frame C and at their rear ends to the side beams A.

50 A shaft D is journaled on the side beams A, just above the frame C, and has secured near its ends toothed pinions d, which mesh

with segmental racks c on the frame C. A third toothed wheel d' is mounted on the shaft D, and a handle D', bifurcated at its 55 lower end to straddle the wheel d', is also mounted on the said shaft and is provided with a sliding catch d², the lower end of which engages the toothed wheel d' and the upper end of which is provided with a handle d³, by 60 which the lower end may be raised clear of the toothed wheel d'. A pawl d⁴ is mounted in the frame of the machine and adapted to engage the toothed wheel d' to prevent rotation thereof when the handle D' is released. This 65 pawl may be disengaged from the toothed wheel d' by raising the forward extension thereof, as will be readily understood. By turning the shaft D by means of the handle D' the pinions d will be caused to run up or 70 down the segmental racks c, and thus raise or lower the front of the main frame of the machine.

A secondary frame E is suspended below each of the side beams A of the main frame, 75 and in these frames E are journaled shafts F, G, and H, each shaft being provided with a number of sprocket-wheels f, g, and h, respectively. The rear one of these shafts F has hung thereon a series of arms F', which 80 are curved forwardly and downwardly and provided beneath their forward ends with rollers f', which run on the ground and support the forward ends of the arms F', keeping them just out of contact with the ground. 85

A shaft I is journaled upon the side beams A above the frames E and is provided with a number of sprocket-wheels i between the two side beams and with a sprocket-wheel i' at one end. 90

A series of sprocket-chains K run on the sprocket-wheels i, g, and h and have fingers or carriers K', (shown more clearly in Fig. 5,) each carrier consisting of a curved finger k', pivoted on one of the pins k of the chains and held in position by links or arms k², which are pivoted at one end to one of the pins k and at their other ends to the said fingers k', thus holding said curved fingers at approximately right angles to the chains. 95

A shaft L is journaled on the side beams A in rear of the forward pair of uprights A² and carries a large sprocket-wheel l at one end, a pair of small sprocket-wheels l', and a 100

bevel gear-wheel p . The small sprocket-wheels l' are connected by sprocket-chains O with sprocket-wheels b' on the axle B' of the rear wheels B , and the large sprocket-wheel l is connected by a sprocket-chain O' with the sprocket-wheel i' on the shaft I . Thus when the rear wheels revolve the chain O will drive the shaft L and the chain O' will drive the shaft I , which in turn will drive the carrier-chains K . The fingers on the carrier-chains are arranged to move rearwardly near enough to the ground to pick up the cut cane and are so located that they will begin their upward movement with their ends between the arms F' . Thus they will push the cane upwardly upon the arms F' until it is picked up by the fingers of the elevator-chains, which will now be described.

A shaft M is journaled near the upper ends 20 of the forward pair of uprights A^2 and is provided with a number of sprocket-wheels m , a bevel-pinion m' , and a bevel gear-wheel m^2 , the latter being at one end outside of the main frame, for a purpose to be described hereinafter.

The elevator-chains M' pass around the sprocket-wheels m and f and are provided with fingers m^3 , made precisely like the fingers on the carrier-chains K . These fingers 30 m^3 take the cane from the arms F' and the fingers k' and lift it to the platform N on top of the main frame.

The platform N , as shown in Fig. 4, is in the form of a quadrant, having slots n along 35 its front edge for the fingers m^3 to pass through as they turn over the sprocket-wheels m , and it is also provided with downwardly-curved fingers n' , over which the cane passes, and which fingers assist in raising the cane from 40 the fingers m^3 on the elevator-chains M' .

The shaft M is driven from the shaft L by means of a shaft P , which is journaled in bearings l^4 and m^4 , hung on the shafts L and M , respectively, and having at its lower end 45 a bevel gear-wheel p , meshing with the bevel gear-wheel l^2 on the shaft L , and at its upper end a bevel gear-wheel p' , meshing with the bevel-pinion m' on the shaft M .

A vertical shaft Q is journaled in bearings 50 a on one of the vertical frame-pieces A^2 and is provided with a bevel-pinion q , meshing with the bevel gear-wheel m^2 on the shaft M , from which the vertical shaft Q is driven.

Upon the shaft Q , slightly above the platform N , are secured a number of arms Q' , having depending teeth q' , which sweep over the platform N in the direction of the arrow in Figs. 2 and 4 and take the cane from the fingers m^3 when it is deposited on the platform N , sweeping it around the said platform, giving it a quarter-turn, and finally dropping it from the edge n^2 of the platform into a vehicle, (not shown,) which when the machine is in operation is driven along at 65 the side of the machine.

The platform N is provided with upwardly-extending flanges N' and N^2 along its curved

sides, which prevent the cane from leaving the platform until it reaches the edge n^2 .

The top of the shaft Q is extended somewhat above the arms Q' , and to the upper end thereof are secured the ends of chains q^2 , having their other ends secured to the arms Q' to support the same in a horizontal position above the platform N .

The machine as herein described is arranged to deliver the cane at the right-hand side; but it will be obvious that by slight changes in the shape of the platform and in the position of the vertical shaft Q it could be made to deliver at the left-hand side. It will also be obvious that other slight changes or modifications might be made in the machine without departing from the spirit of the invention.

In operation the machine is driven over the field after the cane has been cut, a wagon or other suitable vehicle (not shown in the drawings) being driven along close to the delivery side thereof. The cane is picked up by the arms F' and the fingers k' on the carrier-chains, which latter carry it up the arms F' until the fingers m^3 on the elevator-chains pick it up and carry it to the platform N . Here the fingers q' on the revolving arms Q' sweep it through one-quarter revolution and push it over the edge n^2 of the platform into the wagon or other receptacle.

The gearing of the several shafts is so proportioned that the elevator-chains M' run about twice as fast as the carrier-chains K and the arms Q' revolve about twice as fast as the shaft M .

The machine may be drawn by horses, mules, or other suitable motive power, and the draft-gear, not being a part of my present invention, is not shown or described.

Having thus described my invention, what I claim, and desire to secure by Letters Patent of the United States, is—

1. In a cane-loader, the combination with the main frame and supporting-wheels carried thereby, arms carried by said frame, carriers supported in said frame, a table mounted upon said main frame, rotating arms, having teeth adapted to move over said table, and elevators adapted to take the cane from said carriers and deliver the same upon said table, and means for operating the several parts, substantially as described.

2. In a cane-loader, the combination with a main frame, a shaft having pinions journaled on said main frame; of a second frame below the main frame, wheels supporting said second frame, links pivoted to said main frame and to said second frame, a segmental rack on the second frame meshing with the pinions on the main frame, and means for turning said pinions to elevate or depress said main frame, substantially as described.

3. In a cane-loader, the combination of a frame, supporting-wheels carried thereby, arms mounted beneath said frame, carriers also mounted beneath said frame, adapted to

coöperate with said arms, a table mounted upon said frame, elevators adapted to convey material from said carriers to said table, an upright shaft mounted in said frame, a plurality of radial arms secured to said shaft, said arms being adapted to pass over said table, and rakes carried by said arms, adapted to receive the material from said elevators, and slide it over said table into a suitable receptacle, substantially as described.

4. In a cane-loader, the combination with a main frame, supporting-wheels carried by said frame, devices for picking up and elevating the cane, of a second frame, provided with wheels supporting one end of said main

frame, links connecting said main and second frames, segmental racks carried by said second frame, and a shaft mounted in said main frame, and having pinions meshing with said segmental racks, for elevating and depressing said main frame, thereby raising or lowering said picking-up and elevating devices, substantially as described. 20

In testimony whereof I affix my signature in presence of two witnesses.

JOSEPH D. MARTINEZ.
